UNITED STATES PATENT OFFICE.

DOROTHY W. DAY, OF CHICAGO, ILLINOIS.

DESIGN FOR A RADIATOR CASING.

Application filed May 15, 1925. Serial No. 13,447. Term of patent 14 years.

To all whom it may concern:

Be it known that I, DOROTHY W. DAY, a citizen of the United States, residing at Chicago, county of Cook, and State of Illinois, have invented a new, original, and ornamental Design for Radiator Casings, of which the following is a specification, reference being had to the accompanying drawing, forming a part thereof.

Figure 1 is a front elevational view of a radiator casing, showing my new design. Figure 2 is an end view of the same.

I claim:

The ornamental design for a radiator casing, as shown.

DOROTHY W. DAY.
